MILK BOTTLE HOLDER

Filed April 17, 1928

UNITED STATES PATENT OFFICE

JAMES N. DAUGHERTY, OF MASURY, OHIO

MILK-BOTTLE HOLDER

Application filed April 17, 1928. Serial No. 270,725.

This invention relates to a milk bottle holder and has for its object to provide a structure which is simple, inexpensive to manufacture, sanitary, handy, convenient, compact, easy to handle, thoroughly efficient and reliable in use, and otherwise well adapted to the purpose for which it is designed.

With the above and numerous other objects in view as will appear as the description proceeds, the invention resides in certain novel features of construction and in the combination and arrangement of parts as will be hereinafter more fully described and claimed.

15 In the drawing:

Figure 1 is a side elevation of the holder embodying the features of my invention, showing the lid in section.

Figure 2 is a front elevation thereof showing the base in section.

Figure 3 is a top plan view thereof.

Referring to the drawing in detail, it will be seen that the numeral 5 denotes the base which is provided with side flanges 6 and an end flange 7 at the front thereof. These flanges 6 and 7 rise therefrom and the flanges 6 extend beyond the rear edge of the base as is shown in Figure 1. An L-shaped bracket 8 has its lower horizontal arm fixed to the center of the base 5 by means of screws 9 or in any other preferred manner. The back 10 is secured to the vertical leg of the bracket 8 by means of screws 11 or in any other suitable manner. This back is provided with openings 12 so that screws or the like may be inserted therethrough and engaged in the wall or other suitable support.

A hinge 14 is mounted at the upper end of the back. A lid 15 is engaged with the hinge so that it may be swung to a horizontal position as shown in Figure 1, over a milk bottle seated on the base, and the lid is provided with a recess 16 in the bottom thereof into which the mouth of the bottle will extend. The base 45 5 is provided with a plurality of circulating openings 18. This holder provides a sanitary and convenient means of handling milk after it is delivered to the home. The method now used in delivering milk to the homes by dairies and other agencies is to set the bot-

ties along side walks, porches, and many unsanitary places where it may be molested in several different ways, namely, prowlers, children playing in the streets, dogs, cats and the like. The features of this holder is to 55 eliminate these disadvantages by having the holder attached to the sides of the buildings, hallways or kitchens, where milk may be placed inaccessible to these annoyances to maintain it pure. The holder is so constructed that there is a free air circulation around the bottle at all times. It is also so constructed as to hold the bottle very firmly, it being impossible for the bottle to be removed without first raising the lid which fits 60 over the mouth of the bottle. This lid, which fits over the mouth of the bottle, also protects the paper cap which is used in the mouth of the milk bottle.

No clamps or springs are necessary to support the bottle. It is thought that the construction, utility, and advantages of this invention will now be quite apparent to those skilled in this art, without a more detailed description thereof. The present embodiment of the invention has been disclosed in detail, merely by way of example, since in actual practice it attains the features of advantage enumerated as desirable, in the statement of the invention and the above description. 70 75 80

It will be apparent that changes in the details of construction, and in the combination and arrangement of parts may be resorted to, without departing from the spirit or scope of 85 the invention as hereinafter claimed or sacrificing any of its advantages.

Having thus described my invention, what I claim as new is:

A milk bottle holder comprising a base including a bottom plate, side flanges carried by the plate and a front flange carried by the plate, a vertical back plate extending upwardly from the base and disposed between the side flanges, an L-shaped bracket having 90 one arm secured to the bottom face of the bottom plate and its other arm to the front face of the back plate for holding the same in position, a cover plate, and a hinge having 95 its beads secured respectively to the upper 100

edge of the back plate and the cover plate,
the rear edge of the cover plate engaging the
front face of the back plate when in its low-
ered position, whereby the cover plate will
5 be held over and spaced from the top of a
bottle, when the same is placed on the base,
as and for the purpose specified.

In testimony whereof I affix my signature.
JAMES N. DAUGHERTY.
